Office Action issued on Feb. 17, 2015 in Japanese Application No. 2014-018606 (with translation).

Primary Examiner — Prabhakar Deshmukh

(74) *Attorney, Agent, or Firm* — Nixon & Vanderhye PC

(57) **CLAIM**

The ornamental designs for portable computer, as shown and described.

DESCRIPTION

FIG. 1 is a front perspective view of a first embodiment of a portable computer showing our new design;
FIG. 2 is a rear perspective view thereof;
FIG. 3 is a front view thereof;
FIG. 4 is a back view thereof;
FIG. 5 is a top view thereof;
FIG. 6 is a bottom view thereof;
FIG. 7 is a right view thereof;
FIG. 8 is a left view thereof;
FIG. 9 is a front view thereof in a folding state;
FIG. 10 is a right view thereof in a folding state;
FIG. 11 is a front perspective view thereof in a folding state;
FIG. 12 is a rear perspective view thereof in a folding state;
FIG. 13 is a front perspective view of a second embodiment of a portable computer showing our new design;
FIG. 14 is a rear perspective view thereof;
FIG. 15 is a front view thereof;
FIG. 16 is a back view thereof;
FIG. 17 is a top view thereof;
FIG. 18 is a bottom view thereof;
FIG. 19 is a right view thereof;
FIG. 20 is a left view thereof;
FIG. 21 is a front view thereof in a folding state;
FIG. 22 is a right view thereof in a folding state;
FIG. 23 is a front perspective view thereof in a folding state;
and,
FIG. 24 is a rear perspective view thereof in a folding state.
